UNITED STATES PATENT OFFICE.

FREDRICK MONIER, OF NEW BRITAIN, CONNECTICUT.

SPUR.

SPECIFICATION forming part of Letters Patent No. 424,719, dated April 1, 1890.

Application filed December 20, 1889. Serial No. 334,397. (No model.)

To all whom it may concern:

Be it known that I, FREDRICK MONIER, of New Britain, in the county of Hartford and State of Connecticut, have invented certain 5 new and useful Improvements in Spurs, of which the following is a full, clear, and exact description, whereby any one skilled in the art can make and use the same.

My invention relates to the class of spurs 10 that are made up in sections; and my invention relates to certain improved attaching means, whereby the rim and neck that are in the first instance made of separate pieces are permanently secured to each other in a simple and extremely durable manner.

My invention consists in the details of the several parts making up the spur as a whole, and in their combination, as more particularly hereinafter described, and pointed out 15 in the claim.

Referring to the drawings, Figure 1 is a side view of a completed spur. Fig. 2 is a detail top view of the rim-blank. Fig. 3 is a detail front view of the rim-blank. Fig. 4 is 20 a detail top view of the neck. Fig. 5 is a detail view in section through the rim-blank and through the neck-blank, these parts being shown in proper relation to illustrate the manner of attaching the parts together.

In the accompanying drawings, the letter 25 *a* denotes a spur as a whole, *b* the rim, *c* the neck that is secured thereto, and *d* the rowel or wheel. These parts are usually made of metal cast to shape, and my improvement enables them to be made of iron, malleable iron, or steel, the rim being cast to shape and forming a blank *b'*, having on the inner sides the recesses *b²* at the extreme front ends of the rim, where the means for attachment of the 30 strap are usually arranged, while on the center of the curve at the rear of the rim is a projecting interlocking part *b³*. This extends vertically on the central rear portion of the rim and is bounded, preferably, at each side 35 by a flattened surface *b⁴*. The locking projection *b³* is preferably tapered in two directions, as shown, so that it will fit closely into

a socket *c'*, formed in the end of the neck *c*. This cut in the neck-blank is formed in the reverse of the projection, so that when the 50 lug or tenon *b³* is fitted within the socket *c'* the two parts—the rim and the neck—will be securely locked together, the neck having on each side of the socket *c'* flattened surfaces *c²*, that fit snugly against the corresponding 55 surfaces *b⁴* of the rim.

The neck is provided with the usual forked end *c³*, within which the rowel *d* is supported by the pivot-pin *f* or screw firmly secured in place.

It is evident that it is not essential to my improvement that the tenon should be formed on the rim, as an equally secure joint formed of interlocking lugs and sockets on the principle described can be made with the projecting lug on the neck, while the socket is formed in the rim; but the form of the improvement as shown in the drawings is the preferred form. After the rim and neck have been fastened to each other, as described, by means 65 of the inner engaging tenon or lug and socket the parts are soldered or brazed together or closed upon each other by pressure.

The recesses *b²* afford room for heading over or riveting the inner end of the stud *g*, on 70 which the attaching-strap may be buttoned. It also affords room for the fold of the link *h*, of thin metal, that supports a chain or attaching-strap that lies below the shank of the shoe and forms part of the attaching means. 75

I claim as my invention—

In a spur, in combination with a rim having on its rear end an upright projecting tapered lug bounded on each side by bearing-surfaces, a neck having in its rear end a corresponding and tapered socket adapted to receive the projection on the rim, the said socket being bounded on each side by bearing-surfaces fitting the corresponding bearing-surfaces on the rim, all substantially as described. 85 90

FREDRICK MONIER.
